UNITED STATES PATENT OFFICE

MILTON H. BALLARD AND DONALD G. MCLEAN, OF BEVERLY, MASSACHUSETTS, AS-SIGNORS TO UNITED SHOE MACHINERY CORPORATION, OF PATERSON, NEW JERSEY, A CORPORATION OF NEW JERSEY

PRESS

Application filed July 6, 1929. Serial No. 376,463.

This invention relates to presses and more particularly to presses of the kind employed for cutting sheet material by the use of freely movable dies and is herein illustrated as 5 embodied in a twin clicking machine of the type disclosed in United States Letters Patent No. 1,500,101, granted July 8, 1924 upon an application filed in the name of M. H. Ballard, although it is to be understood that 10 the invention is not limited to embodiment in machines of that type.

Machines of the type referred to characteristically comprise a presser member mounted upon a post adjacent to a work-supporting 15 bed and arranged to swing laterally over the bed into position for operating upon work located on the bed and to move toward and away from the bed in pressure-applying operations upon the work. The presser member 20 and post are commonly reciprocated by mechanism comprising an eccentric and movable parts including a connecting rod or shaft making operative connection between the post and eccentric. During operation 25 of the machine such parts are subject to comparatively great stresses, frequently as high as several tons, particularly at such times as when the machine becomes stalled with the eccentric at lower dead center by reason of 30 careless operation upon heavy leather or upon many plies of fabric.

In view of the foregoing, it is an object of the present invention to provide an improved clicking machine in which the driving parts 35 are constructed and arranged particularly to withstand the great stresses to which they are subjected without, however, sacrificing any of the advantages of clicking machines as heretofore constructed. To this end and as illustrated, there is provided a clicking machine having a cutting block, a post, and a presser member movable toward and away 40 from the cutting block, together with means 45 comprising a driving member for producing reciprocations of the presser member and post and which is operatively connected to the post in such manner as to provide for lateral movement of the presser member over 50 the block and relative angular movement of

the post and driving member. Preferably and as illustrated, the driving member comprises a connecting rod having an enlarged head at one end thereof provided with concentric spherical surfaces adapted to be engaged by and secured between bearing surfaces in the upper end of the post, with the result that the connecting rod and post are arranged substantially for universal movement relatively to each other. This construction provides for the rotation of the post upon the connecting rod in moving the presser member laterally over the cutting block and at the same time insures that the forces which would tend to break or bend 55 the rod and other driving parts will act in the direction of the axis of the rod thereby practically eliminating any likelihood of breaking or bending them.

Other objects of the invention and features 60 of construction will be apparent from the following description and will be pointed out in the claims.

In the drawings,

Fig. 1 is a view in front elevation and partly 65 in section of a clicking machine illustrating one embodiment of the invention; and

Fig. 2 is a side view partly in section showing details of the post and connecting rod 70 constructions.

As shown in Fig. 1, the machine comprises two C-shaped frame members 10, secured together by tie rods 12 and 14 and having between them a bed 16 which supports a cutting block 18. Slidably mounted in each of the frame members 10 is a post 20 having rigidly secured thereto a presser member 22 which is movable with the post 20 toward and away from the block 18 and movable laterally over the block in locating the presser member in operative relation to work supported upon the block. The mechanisms for driving the posts 20 on opposite sides of the block 18 are substantially identical so that only the mechanism to the right of the block 80 (in Fig. 1) will be described. The presser member 22 and post 20 are reciprocated by mechanism comprising a fly-wheel 23 loosely mounted on a shaft 24 which has an eccentric 85 for driving an upright shaft or connecting 90

rod 28 operatively connected to the post 20. Operation of a clutch (not shown) for causing the fly-wheel 23 to engage with and to rotate the shaft 24 is initiated by means of a 5 starting handle 30 mounted on the presser member 22 and operative through connections 32, 34, 36 and 38 to trip a clutch lever 40. The bed 16 is mounted for vertical adjustment, to compensate for different heights of cutting 10 blocks, by means of screws 42 only one of which is shown. Each of the screws 42 is carried by a bracket 44 secured to the frame and is arranged for rotation to raise or lower the bed by a worm gear 46 on a shaft 48 which is 15 operated by a hand wheel 50. For further details of construction and operation of certain of the parts above described reference may be had to the aforementioned Letters Patent.

The novel mechanism for operatively securing the post to the connecting rod will now be described. Within the upper end of the post 20 is mounted a screw-threaded sleeve 52 having a spherical bearing or seat surface 54 which is arranged to receive a corresponding 25 spherical surface 56 upon a ball-shaped enlargement or head 58 at the upper end of the connecting rod 28. In the extreme end of the connecting rod is a recess 60 the lower portion of which is spherical in shape. Within the 30 recess 60 is positioned a hardened steel bearing member 62 which is hemispherical in shape, the flat portion thereof being upwardly disposed. The weight of the post 20 and presser member 22 is borne by the flat surface 35 of the hemispherical member 62 to which it is transmitted by an adjusting pin in the form of a screw 64 carried by a cap 66 secured to the sleeve 52 by bolts 68. In assembling the parts the screw 64 is moved downwardly against the 40 flat surface of the bearing member 62 to take up the play between the member 62 and the walls of the recess 60 and between the spherical surface 56 and the seat 54 of the sleeve, the parts being held in adjusted position by a 45 set screw 70 in the cap 66.

The spherical surface 56 of the head 58 and the spherical surface of the recess 60 are concentric, their centers of curvature coinciding substantially at the center of the 50 flat surface of the bearing member 62 thereby providing a universal mounting for the post 20 by which the post can be turned upon the connecting rod 28 while at the same time permitting angular displacement of the 55 rod as it is driven by the eccentric 26. It is to be noted that the spherical bearing surface 56 of the head 58 engages the sleeve 52 only over a comparatively small surface which is disposed substantially normal to 60 the direction of application of forces acting through the connecting rod with the result that the tendency of the connecting rod to grip the sleeve 52 is reduced to the extent that there is very little resistance to relative movements of the rod and post.

On screw threads 72 at the lower end of the shaft or connecting rod 28 is an eye 74 which engages the eccentric 26 by which the rod is driven. The lower end of the rod 28 is provided with two conical surfaces 73 the 70 axes of which extend radially of the rod. The eye 74 is provided with a set-screw 75 also extending radially of the rod and having a conical surface 76. Upon inward movement of the set-screw, the surface 76 engages one of the surfaces 73, forcing the rod and eye in opposite directions, thereby jamming the threads 72. The end of the set-screw, in addition, serves as a positive lock 75 to prevent loosening of the screw-threaded connections. To facilitate the alinement of one or another of the conical surfaces 73 with the set-screw 75, the rod 28 is provided with a groove 77 so spaced from the surfaces 73 that when the rod 28 is threaded into the eye 74 with the groove positioned close to the upper surface of the eye 74, the axes of the surfaces 73 lie approximately in the plane of the axis of the set-screw 75 with the result that the rod need be turned only slightly to aline one of the surfaces 73 with the set-screw. This construction is effective firmly to secure together the connecting rod and eye thereby to prevent their relative rotation.

The lower portion of the eye 74 carries a wick 78 which picks up oil from a recess in the frame (not shown) to provide for the lubrication of the bearing surfaces of the eye and the eccentric 26.

To provide for adjustment of the presser member toward or away from the block to compensate for the various heights of dies used, the cap 66 is provided with a hand wheel 80 by which the sleeve 52 can be rotated. Rotation of the sleeve 52 will effect a raising or lowering of the post and presser member relatively to the connecting rod 28 the end of which in its uppermost position is at a predetermined height above the cutting block when the machine is at rest. The post is retained in its adjusted position by a friction device comprising a plunger 82 located in the post and arranged for engagement with one or another of a plurality of notches 83 in a flange 84 on the cap 66. The plunger 82 when positioned in a notch exerts sufficient pressure upon the flange, under influence of a spring 86, to prevent relative rotation of the post which would vary the height of the presser member relatively to the cutting block 18.

For lubricating the bearing surfaces of the connecting rod and sleeve there is provided an oil opening 88 extending through the central portion of the screw 64. Oil which is inserted through an oil cup 90 at the top of the screw will pass down onto the surface of the bearing member 62 and then into the spherical portion of the recess 60. The overflow of oil from the recess passes 125

down along the outside of the head 58 of the connecting rod and between the spherical surface 56 and the seating surface 54 in the sleeve 52.

5 In the use of the machine sheet material is placed upon the cutting block 18, a die or dies are located on the work for cutting operations thereon, and one of the presser members 22 is swung laterally into position 10 over the work, the weight of the member 22 and the post 20 being rotatably supported by the screw 64 which bears upon the hemispherical member 62 at the top of the connecting rod 28. The handle 30 is then depressed, 15 thereby initiating rotation of the eccentric 26 to produce a pressure-applying operation of the presser member. It will be clear that rotation of the eccentric 26 from its position of rest as shown in Fig. 2 will pull the connecting rod downwardly and, through the head 58 acting upon the seat 54, will force the post 20 and presser members 22 downwardly. Upon upward movement of the rod the presser member and post are raised by 20 positive engagement of the rod with the screw 64. For any position of the eccentric 26 the connecting rod will so position itself by means of its universal connection with the post that the forces to which the rod is subjected will act in the direction of its axis, instead of at an angle thereto, thereby eliminating any likelihood of bending the rod.

Having described our invention, what we claim as new and desire to secure by Letters 35 Patent of the United States is:—

1. A clicking machine comprising a cutting block, a hollow post, a presser member rigidly secured to the post, a driving member extending through the post for moving the post 40 and presser member heightwise of the cutting block, and a ball-and-socket connection located within the post near the upper end thereof for connecting the post to one end of the driving member to provide for angular 45 movement of the presser member relatively to the cutting block and for relative angular movement between the driving member and post during movement of the post heightwise of the cutting block.

50 2. A clicking machine comprising a post, a presser member secured to the post, and means for supporting the post comprising an upright shaft extending through the post and having at one end thereof an enlargement 55 provided with a spherical bearing surface, said enlargement having a recess, the post having a projection extending into the recess for supporting the weight of the post and the post also having a spherical seating surface making engagement with a spherical surface on the shaft.

60 3. A clicking machine comprising a post, a presser member secured to the post, a connecting rod for producing reciprocations of the presser member and the post and extend-

ing through said post, and means for securing the post to the connecting rod comprising a spherical seat within the post, a pin secured to the upper portion of the post, and an enlargement on the connecting rod constructed and arranged to be clamped between the seat and the pin.

4. In a clicking machine a post, a presser member secured to the post, a shaft for producing reciprocations of the post and presser member having at its upper end an enlargement provided with a spherical seating surface and a spherical recess, the post having a spherical seat for engagement with the spherical surface of the shaft, and a member for engaging the walls of the recess for securing the post to the shaft.

5. A clicking machine comprising a frame, a hollow post slidably mounted in the frame and having therein spherical bearing surfaces, a presser member secured to the post, an eccentric for producing reciprocations of the post and presser member, and a shaft for supporting the post having one of its ends operatively connected to the eccentric and having its other end in engagement with said bearing surfaces.

6. A clicking machine comprising a hollow post having a plurality of spaced spherical bearing surfaces, a driving member extending through the post and having an enlargement at one end thereof positioned between the bearing surfaces, and means for clamping the enlargement of the driving member between said surfaces to secure together the post and driving member.

7. A clicking machine comprising a post, a shaft extending through the post and having an enlarged portion at the upper end thereof, said enlarged portion having a plurality of spherical bearing surfaces, and means on the post for engaging the bearing surfaces to secure the post to the shaft.

8. A clicking machine comprising a shaft having two curved bearing surfaces, a post surrounding the shaft and having a bearing surface adapted for engagement with one of the bearing surfaces on the shaft, a movable member having a bearing surface adapted for engagement with the other bearing surface on the shaft, and means associated with the post to clamp the bearing surfaces of the shaft between the bearing surface of the post and that of the movable member.

9. A clicking machine comprising a post, a presser member secured to the post, a cutting block, means for producing movements of the member toward and away from the cutting block comprising a sleeve secured to the upper portion of the post and having a spherical seating surface, a connecting rod extending through said sleeve and having a spherical portion bearing upon said seating surface, the connecting rod having a spherical recess formed in the end thereof, a hemi-

spherical member positioned in the recess, and a cap secured to the end of the post and having a pin extending therethrough for engaging the hemispherical member to secure the post to the connecting rod.

In testimony whereof I, the said MILTON H. BALLARD, have signed my name to this specification. **MILTON H. BALLARD**

MILTON H. BALLARD.

10 In testimony whereof I, the said DONALD G. MCLEAN, have signed my name to this specification.
